UNITED STATES PATENT OFFICE.

JOHN F. SCOTT, OF EVANSVILLE, INDIANA, ASSIGNOR TO ST. LOUIS CAR COMPANY, OF ST. LOUIS, MISSOURI, A CORPORATION.

DOOR-CHECK.

SPECIFICATION forming part of Letters Patent No. 736,639, dated August 18, 1903.

Application filed November 21, 1902. Serial No. 132,211. (No model.)

To all whom it may concern:

Be it known that I, JOHN F. SCOTT, a citizen of the United States, residing in Evansville, in the county of Vanderburg and State of Indiana, have invented certain new and useful Improvements in Door - Checks, of which the following is a full, clear, and exact description, reference being had to the accompanying drawings, forming part of this specification.

My invention relates to a catch for receiving and holding the handles of vestibule-car doors when they are swung into open condition.

15 The invention consists in features of novelty hereinafter fully described, and pointed out in the claims.

Figure I is a view illustrating the platform of a vestibule-car and showing in cross-section a door equipped with my catch. Fig. II is a face view of the catch with the door-handle shown in engagement therewith. Fig. III is a view, partly in horizontal section and partly in plan, of my catch and a door-handle arranged in engagement therewith. Fig. IV is a view showing modification of the finger of the catch.

20 A designates the platform of a vestibule-car, and B and C are the sections of a door such as used to close the passage-way between said platform and the steps associated therewith.

25 1 designates a handle-housing mounted in the section C of the door, and 2 is the door-handle, oscillatively mounted in said housing.

30 3 designates a dish-shaped plate attached to the door-section B and set thereinto so as to occupy a position in alinement with the

handle-housing 1 and into which the handle is adapted to enter when the sections are closed 40 together, as illustrated in Figs. I and III.

4 designates a finger carried by the dished plate 3 and extending outwardly from the base of the recess in said plate in a position to be engaged by an arm of the handle 2 when 45 the door-sections B and C are brought together. The finger 4 is of hook form, as seen most clearly in Fig. III, and its point 5 is curved rearwardly at 6 to receive an arm of the handle 2 and provide for the riding of the 50 handle along the end face of the finger-hook when the door-sections are brought together. The handle-arm after passing the finger-hook swings into the position seen in Figs. II and III in the rear of the hook and is held securely against accidental disengagement. The finger 4 may be formed integral with the dished plate 3, as seen in Figs. II and III, or it may be in the form shown in Fig. IV, in which it is indicated as 4^a and is shown riveted to the plate. 55 60

I claim as my invention—

1. A catch for door-handles of the character named comprising a dished plate, and a hooked finger carried thereby adapted to receive the engagement of a door-handle, substantially as set forth. 65

2. A catch for door-handles of the character named, comprising a dished plate, a finger carried by said plate, and a hook carried by said finger and having a curved outer face, substantially as set forth. 70

JOHN F. SCOTT.

In presence of—

E. S. KNIGHT,
M. P. SMITH.
